US0D1019747S

(12) **United States Design Patent** (10) **Patent No.:** **US D1,019,747 S**
(45) **Date of Patent:** **** Mar. 26, 2024**

(54) **WEARABLE DEVICE**

(71) Applicant: **Amazon Technologies, Inc.**, Seattle, WA (US)

(72) Inventors: **Elliot Kim**, Los Gatos, CA (US); **Niranjan Madanmohan Bhatia**, San Jose, CA (US); **Jihyun Park**, Cupertino, CA (US)

(73) Assignee: **AMAZON TECHNOLOGIES, INC.**, Seattle, WA (US)

(**) Term: **15 Years**

(21) Appl. No.: **29/704,993**

(22) Filed: **Sep. 9, 2019**

(51) LOC (14) Cl. **16-06**

(52) U.S. Cl.

USPC **D16/309**

(58) **Field of Classification Search**

(57) **CLAIM**

The ornamental design for a wearable device, as shown and described.

DESCRIPTION

FIG. 1 is a top, front perspective view of a wearable device;

FIG. 2 is a bottom, back perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the wearable device that form no part of the claimed design.

1 Claim, 8 Drawing Sheets
